UNITED STATES PATENT OFFICE.

SIDNEY W. BRAINARD, OF AKRON, OHIO, ASSIGNOR TO THE AUTOMATIC SPRINKLER COMPANY OF AMERICA, A CORPORATION.

AUTOMATIC FIRE-EXTINGUISHER SYSTEM.

1,165,386.

Specification of Letters Patent. Patented Dec. 28, 1915.

Application filed July 1, 1911. Serial No. 638,541.

To all whom it may concern:

Be it known that I, SIDNEY W. BRAINARD, a citizen of the United States, residing at Akron, in the county of Summit and State of Ohio, have invented new and useful Improvements in Automatic Fire-Extinguisher Systems, of which the following is a specification.

This invention relates to improvements in automatic fire-extinguisher systems, and the object is to provide a valve of simple construction for automatically connecting the sprinkler system with the water supply upon the opening of one or more of the sprinklers caused by the excessive heat generated by the fire, having a very simple and effectively operating tripping-mechanism.

With the above object in view, the invention consists in the novel features of construction hereinbefore fully described, particularly pointed out in the claims, and clearly illustrated by the accompanying drawings, in which—

Figure 1 is a sectional view, showing the valve-mechanism in normal position, closing communication between the system and water supply, and Fig. 2, a similar view, showing the position of the parts when the valve has been tripped and such communication established.

Referring now more particularly to the drawings, the numeral 1 designates the valve-body or casing, provided with a water-inlet 1^a connected with the water supply and having a seat 2 for the inwardly opening valve 3 which is pivotally mounted in the body or casing 1. This valve is normally held to its seat by a toggle consisting of two members 4 and 4^a. Member 4 rests at its free end in a depression 4^b formed in the inner face of the valve and at its opposite end is formed with a loop 4^c to receive a lug 7^a carried by an arm 7^b projecting from the end of a sliding plunger 7. The lug 7^a, when the toggle is in position holding the valve to its seat, bears against a seat 7^c formed in member 4. Member 4^a is formed of two parts, 5 and 6, the part 5 having a loop 5^a on one end to receive a pin or stud 25 carried by the valve-body or casing and having its opposite end screw-threaded for adjustable connection with the other part 6 which is in the form of a nut having a projecting-portion 6^a seated in a depression 7^d in the arm 7^b of the sliding plunger. When

the parts are in position holding the valve closed, the member 4 of the toggle bears against the valve and the lug 7^a, while the member 4^a bears against the arm 7^b of the plunger and the pin 25. The valve is thus held positively to its seat against the pressure of the water-supply until the plunger is moved forwardly to break the toggle.

The valve-body is provided with an outlet provided with a check-valve body 37 having a seat 35 for the check-valve disk 36 which is normally held thereon by the air-pressure in the system with which the valve-body 37 is connected. This check-valve excludes the air pressure from the main valve-body or casing 1.

The body or casing 1 is formed of two chambers one containing the mechanism hereinbefore described and the other the tripping-mechanism and the wall or partition separating these two chambers is provided with a bushing 8 in which the plunger 7 slides, said plunger having a valve portion 7^c at its inner end which, when it is in forward position, engages a seat 8^a formed in the bushing and prevents escape of water from the chamber in which the toggle mechanism is located to that in which the tripping-mechanism is placed.

The plunger 7 is operated by a weight 11 which is pivotally supported on a pivot-pin 28. Said weight is provided on one side of its pivot with an operating-arm or lever 29 which works in a slot in the plunger 7 and effects the sliding-movement of the latter.

The numeral 38 designates the air-pot or chamber having a seat 14 for a pivoted disk 15. The air-space in this chamber is in communication with the sprinkler system through the pipe E. The disk 15 is thus held to its seat by air pressure in the system. On the face opposite to that acted on by air pressure, said disk has a centrally-dependent lug 15^a, against which, when the disk is seated, the free end of an intermediate pivoted tripping-lever 12 bears. This lever at its opposite end is formed with a notched or bifurcated portion to be engaged by the hooked end of an arm 33^a pivoted to the weight. This hook-lever 33^a holds up the tripping-weight until the air in the chamber 38 drops below a certain pressure, ordinarily about 13 pounds per square inch in the device at this time. The plunger is

held from movement by a retaining device comprising two members 9 and 10. The part 10 is pivotally attached at one end to the weight and at its opposite end engages a notch in the free end of part 9, which part or member is pivoted at its opposite end to a pin or stud carried by the valve-casing 1, and intermediately of its ends is formed with a seat 9^a receiving a stem 7^a projecting from the end of the plunger 7.

The operation of my improved valve is as follows: Assuming the parts to be in the positions shown in Fig. 1, a sprinkler or several sprinklers open and the air begins to exhaust from the main pipe system, reducing the pressure to a pre-determined point (usually 12 to 14 pounds in air systems, whereas normally about 35 to 40 pounds pressure is carried). The weight 11 exerts itself upon the tripping-mechanism and the disk 15, swinging the latter on its pivot, and the air is rapidly exhausted. Lever 12^a is pulled downward by the weight and the hooked lever 33^a disengages the same. This allows the upwardly extending portion of the weight to be dropped to horizontal position and said weight to strike the pin of a switch for completing a circuit to an electric alarm not shown. As the weight 30 drops, it causes the lever or part 10 to swing on its pivot, which in turn releases lever or part 9 and permits the plunger 7 to be moved forwardly by the arm 29 of the weight. This movement of the plunger 35 breaks the toggle and releases the valve 3 which is unseated by the water pressure. The water unseats the check-valve 36 and fills the entire system. The arm 29 of the weight acts to accelerate the unseating of the valve portion of the plunger, in resetting the mechanism, as normally the body-portion of this valve is open to the atmosphere both through the opening around the plunger and through a ball-drip 24.

When the mechanism is tripped, the valve-disk 15 is lifted somewhat off its seat 14 and the short end of lever 12^a which bears against the centrally-depending lug carried by the disk, passes by this lug and is 50 locked against assuming its normal position until the disk is raised and the end of the lever placed beneath the lug, thereby rendering it impossible to re-set the valve except by manual operation.

In order to set the valve the disk 15 is raised and the end of lever 12^a is placed beneath the depending lug 15^a and air is then admitted above the disk 15. The weight 11 on the end of the tripping lever is then 55 raised and the hooked end of the arm 33^a engaged with the bifurcated portion of the tripping lever 12^a. The valve 3 is then lowered upon its seat and the various parts of the stress and tripping mechanism are set practically in the relations shown in the

drawing after which the stress nut 6 is adjusted with a suitable wrench. The mechanism is then set ready for further operation.

It will be noted that practically all the 70 bearings are the loose or sleeve-bearing type, and these are provided to avoid the bad effects of corrosion, as if close joints were provided and they became corroded, it might result in the valve becoming inoper- 75

Having thus fully described my invention, what I claim as new and desire to secure by Letters Patent of the United States, is—

1. A valve for automatic fire-extinguisher systems, comprising a casing having an inlet connected with a water supply and an outlet connected with the system, a valve disk normally closing said inlet, a toggle-device for holding said valve-disk to its seat, a sliding member having an operative connection with said toggle-device, an air chamber in communication with the system, a disk in said chamber normally held to its seat by air-pressure, a pivoted tripping lever having one end engaging said disk, a pivoted weight for actuating the sliding-member, a hook-member pivotally carried by the weight having its hook-end engaging the opposite end of the tripping lever, whereby the weight is held suspended while the disk is seated, and means for holding the sliding-member from movement operated to release the same by the movement of the weight.

2. A valve for automatic fire extinguisher systems comprising a casing having an inlet connected with a water supply and an outlet connected with the system, a valve-disk normally closing said inlet, a toggle-device for holding said valve-disk to its seat, a sliding member having an operative connection with said toggle-device, an air-chamber in communication with the system, a disk in said chamber normally held to its seat by air pressure, a pivoted tripping lever having one end engaging said disk, a pivoted weight for actuating the sliding-member, a hook-lever pivotally carried by the weight having its hook-end engaging the opposite end of the tripping lever, whereby the weight is held suspended while the disk is seated, means normally preventing movement of the sliding-member comprising a member pivoted at one end in the casing and disposed across the path of movement of the sliding member, and a member pivotally mounted on the weight and engaging the opposite end of the first-mentioned member.

3. A valve for automatic fire-extinguisher systems, comprising a casing having an inlet connected with a water supply and an outlet connected with the system, a valve-disk

normally closing said inlet, a toggle-device for holding said valve-disk to its seat, a sliding-member having an operative connection with said toggle-device, an air-chamber in communication with the system, a disk in said chamber normally held to its seat by air pressure, said disk having a depending lug, a tripping-lever pivoted intermediately of its ends in said casing and having one end adapted to engage the lug of the disk, a pivoted weight for actuating the sliding-member, a pivoted-member carried by the weight adapted to engage the opposite end of the tripping-lever, whereby the weight is held suspended while the disk ¹⁵ is seated, and means for holding the sliding-member from movement, said means operated to release the same by the movement of the weight.

In testimony, whereof, I affix my signature in the presence of two witnesses.

SIDNEY W. BRAINARD.
